UNITED STATES PATENT OFFICE

JOSEPH ANDERSON, LEO V. ANDERSON AND JOSEPH B. ANDERSON, OF LEHI, UTAH

CIRCUIT CLOSER

Application filed February 4, 1932. Serial No. 590,920.

This invention relates to a circuit closer, and it is primarily an object of the invention to provide a device of this kind actuated by a time operating mechanism and which embodies a structure whereby a desired circuit may be closed and opened in predetermined timed sequence.

Another object of the invention is to provide a device of this kind comprising a movable contact member arranged for coaction with a second contact member, said second contact member being adjustable with respect to the movable contact member to regulate or control the period of time with which both of such contacts are in working engagement one with respect to the invention.

The invention also has for an object to provide a device of this kind comprising a movable contact for coaction with what might be termed a stationary contact, together with a stop member arranged for coaction with the movable contact to provide means to assure working engagement between the movable and stationary contacts at substantially a predetermined period of time.

An additional object of the invention is to provide a device of this kind comprising two contacts, one being movable with respect to the other, the movable contact being of a character to have immediate effective engagement with the other contact or release therefrom with the liability of sparking or gapping substantially eliminated.

The invention consists in the details of construction and in the combination and arrangement of the several parts of our improved circuit closer whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawing, wherein:

Figure 1 is a view in elevation of a circuit

closer constructed in accordance with an embodiment of our invention;

Figure 2 is a horizontal sectional view taken substantially on the line 2—2 of Figure 1 looking in the direction of the arrow;

Figure 3 is a diagrammatic view illustrating certain features of the invention as herein comprised.

As disclosed in the accompanying drawing, 1 denotes a body member of desired configuration and formed of any suitable material non-conductive of electricity. This member 1 may be supported by a base bracket 2 or otherwise as the requirements of practice may prefer. Rotatably disposed through the member 1 is a shaft 3 of a material conductive of electricity and which is adapted to be engaged by a coupling 4 with a drive member 5.

The coupling 4 is of a material non-conductive of electricity and the member 5 is adapted to be driven by any desired type of time actuating mechanism, the member 5, however, preferably rotating at a speed to require twenty-four hours to complete a single revolution of the shaft 3.

The shaft 3 is preferably disposed directly through a supporting bearing 6 also of a material conductive of electricity and which is fixedly secured by the screws 7 or the like to the body member 1. One of the screws 7 in the present embodiment of our invention constitutes a terminal connection for a conductor *a* adapted to lead from a suitable source of electrical energy.

In the present embodiment of the invention the member 1 at opposite sides of its vertical center is provided with the arcuate slots 8 concentric to the shaft 3 and slidably arranged within each of the slots 8 is a contact member 9. Each of these members 9 has leading therefrom an electrical conductor *b* leading to a suitable point of translation, as for example a potential illuminating medium. The shaft 3 in the present embodiment of the invention rotates in an anti-clockwise direction and each of the slots 8 has arranged therein in advance of its contact member 9 a stop member 10. Each of the contact members 9 as well as each of the

100

stop members 10 is adapted to be adjusted along its associated slot 8 to a desired selective location in accordance with the desired timed sequence of operation, and one of the 5 slots 8 beyond the contact member 9 is provided with a second contact member 11 in electrical connection by the conductor *c* with a conductor *b* and interposed in this conductor *c* is a resistance coil 12.

10 Each of the contact members 9 and the stop member 10 is held in desired adjusted position in its slot 8 in a conventional manner by a holding nut 4.

15 The shaft 3 carries a rock arm 15 overlying the outer or front face of the member 1 and pivotally connected, as at 16, with the outer extremity of the rock arm 15 is an elongated and relatively broad contact member 17 which, in the present embodiment of the invention, is substantially straight from end to end.

20 Coacting with the rock arm 15 and with the contact member 17 is a spring element 18 which serves to urge the contact member 17 in one direction. This spring element constitutes an intermediate coil surrounding the pivotal mounting 16 for the member 17 with one extremity of the spring element in effective engagement with the rock arm 15 and 25 the opposite extremity in effective engagement with the contact member 17.

25 In the present embodiment of our invention a period of twenty-four hours is required for the rock arm 15 to completely travel around the adjacent face of the member 1, and as the 30 rock arm 15 travels upwardly from the vertical the contact member 17 will come into contact with the stop member 10 at what we might call the "evening" side of the device. 40 The location of the stop member 10 within its slot 8 with respect to the adjacent contact member 9 will determine the period of time required for said contact member 17 to pass from the stop member 10.

45 As the rock arm 15 travels with the contact member 17 in contact with the stop member 10 the spring element 18 will be placed under such tension that immediately upon the contact member 17 passing free from the 50 stop member 10 the spring element 18 will throw the contact member 17 into abrupt engagement with the contact member 9. This is important as it minimizes the liability of 55 sparking or gapping which might otherwise occur and which would have a tendency to impair the efficiency of the device.

When the member 17 comes into engagement with the contact member 9 due to the fact that the rock arm 15 as well as the contact member 17 are conductive of electricity, a circuit will be closed through the conductors *a* and *b* thus assuring the desired translation of electrical energy, as for example an electric lighting system such as employed in 65 chicken houses.

The placement of the stop member 10 with respect to the contact member 9 and, of course, the particular location of the contact member 9 will determine the period of time at which the contact member 17 will come 70 into engagement with the contact member 9. The setting of these members 10 and 9 may be readily done by initially turning the shaft 3 and considering the readings of the conventional time hands with respect to the associated time dial. To facilitate this placement, however, the outer face of the member 1 may have thereon the graduations 19 which, as illustrated in Figure 1 of the drawing, may be placed at one-half hour intervals. As is 80 believed to be obvious these graduations, however, may be otherwise spaced or arranged.

As the contact member 17 passes from the contact member 9 at the "evening" side of the device, said contact member 17 under the influence of the spring element 18 will then be immediately brought into engagement with the contact member 11 which, owing to the interposed resistance in the conductor *c* leading therefrom, will reduce the translation of 90 the current and which is particularly desirable in chicken houses as the glow from the lighting system will be reduced somewhat in simulation of a sunset.

95 It might be mentioned at this time that our improved device can be employed to advantage in connection with chicken houses to assure longer hours of light than would be obtained if depending wholly and entirely upon the sun.

100 It is believed that the coaction and operation of the contact member 17 with the stop member 10 and the contact member 9 in the slot 8 at the "morning" side of the device will be clearly understood from the aforesaid description with respect to the similar members in the slot at the "evening" side of the device.

105 From the foregoing description it is thought to be obvious that a circuit closer constructed in accordance with our invention 110 is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the 115 several parts herein shown in carrying out our invention in practice except as herein-after claimed.

120 We claim:—

1. A circuit closer comprising a member, a rock arm rotatably supported by said member, arcuate slots in the member concentric to the axis about which the rock arm travels, means for connecting the rock arm to a source of electrical energy, a contact member in each of the slots, a stop member in each of the 125 130

slots in advance of the contact member, a contact member pivotally connected to the rock arm and of a length to have contact with a stop member and a first named contact member, and a spring element coacting with the rock arm and the last named contact member for bringing said last named contact member into engagement with the stop member and then to abruptly bring the last named contact member into engagement with the contact member in the same slot as the stop member immediately upon the rock arm travelling a distance to throw the last named contact member free of the stop member.

15 2. A circuit closer comprising a member, a rock arm rotatably supported by said member, arcuate slots in the member concentric to the axis about which the rock arm travels, means for connecting the rock arm to a source of electrical energy, a contact member in each of the slots, a stop member in each of the slots in advance of the contact member, a contact member pivotally connected to the rock arm and of a length to have contact with a stop member and a first named contact member, and a spring element coacting with the rock arm and the last named contact member for bringing said last named contact member into engagement with the stop member and then to abruptly bring the last named contact member into engagement with the contact member in the same slot as the stop member immediately upon the rock arm travelling a distance to throw the last named contact

member free of the stop member, the contact member and stop member in each of the slots being adjustable in the slot one with respect to the other.

3. A circuit closer comprising a rock arm, means for operating the same, means for placing the rock arm in connection with electrical energy, a member, a contact member carried thereby, a stop member carried by said member, said contact member and stop member being adjustable one with respect to the other, an elongated contact member pivotally connected with the rock arm for contact with the stop member and the contact member in timed sequence, and a spring element coacting with the rock arm and the elongated contact member for urging the elongated contact member into effective engagement with either the stop member or the first contact member, said spring element being placed under tension during travel of the rock arm with the elongated member in engagement with the stop member and abruptly throwing the elongated member into engagement with the first named contact member immediately upon the rock arm moving a distance to free the elongated member from the stop member.

In testimony whereof we hereunto affix our signatures.

JOS. ANDERSON.
LEO V. ANDERSON.
